W. W. CRAM

GARTER CLASP

Filed June 2, 1924

UNITED STATES PATENT OFFICE.

WALTER W. CRAM, OF SHELDON, IOWA.

GARTER CLASP.

Application filed June 2, 1924. Serial No. 717,381.

To all whom it may concern:

Be it known that I, WALTER W. CRAM, a citizen of the United States, residing at Sheldon, in the county of O'Brien 5 and State of Iowa, have invented certain new and useful Improvements in Garter Clasps, of which the following is a specification.

This invention relates to improvements in 10 clasp structures.

The primary object of this invention is the provision of a clasp acting upon a novel principle, including a relatively broad clamping surface which may be utilized 15 for supporting articles, such as hosiery, without liability of tearing the hosiery, such as is the case with conventional clasps.

A further object of this invention is the provision of a clasp particularly adapted 20 for supporting hosiery or the like, which includes hingedly connected frame portions with relatively long resilient rollers at the free ends thereof, which act as jaws, and which may be held into a clamping relation, 25 when the frame portions are in a certain position.

Other objects and advantages of this invention will be apparent during the course 30 of the following detailed description.

In the accompanying drawing, forming a part of this specification, and wherein similar reference characters designate corresponding parts throughout the several views,

Figure 1 is a perspective view, showing 35 the manner in which the improved clasp may be used for supporting hosiery, so that the clamping or supporting grip thereof is disposed over a relatively wide portion of the hosiery.

Figure 2 is a cross sectional view taken 40 through the improved clasp, showing the same in clamping position with a garment clamped between the jaw or roller portions thereof.

Figure 3 is a cross sectional view through 45 the details illustrated in Figure 2, showing the jaw or roller portions thereof in an unclamped relation just prior to the snapping of the same into clamped position upon 50 the garment.

Figure 4 is a view showing the portions of the clasp extended, and

Figure 5 is a view showing the relation of the frames and other details of the clasp as they appear in clamped relation. 55

In the drawing, wherein for the purpose of illustration is shown a preferred embodiment of this invention the letter A may generally designate the improved clasp, which may be supported upon the elastic 60 portion B of garters or the like, in order to hold garments C, such as hosiery without liability of tearing such garments, and without liability of becoming detached 65 therefrom when in clamped relation thereon.

Referring to the structure of the improved clasp A, the same preferably includes frames 12 and 13 which support the clamping jaw and roller 15 and 16 respectively thereon. 70

Referring to the structure of the frame 12, the same includes the upper cross portion 20 which is rigidly fixed in the barrel portion 21 of the member 22 to which the frame 13 is hingedly connected. The frame 75 12 furthermore includes the substantially parallel side bar portions 24 and 25 arranged at right angles to the top bar 20. The lower ends of the bar portions 24 and 25, at 26, are laterally outturned or disposed at an obtuse angle with respect to the plane in which the remaining portion 80 of the frame 12 is disposed, and at the outer ends of the obtusely disposed portion 26 a cross bar portion 28 is provided, 85 which fixedly supports a sleeve 29 directly thereon, and upon which sleeve 29 a resilient rubber covering 30 is fixed in frictional engagement therewith. It is thus to be noted that the jaw structure 15 is supported 90 by the cross bar portion 28 at a point laterally of the plane in which the frame 12 is disposed.

The frame 13 is hingedly connected to the lower barrel portion 35 of the connecting element 22; it being preferred that the barrel portion 35 have the end margins thereof disposed inwardly from the end margins of the barrel portion 21, substantially as is illustrated in the drawing. 95 The frame 13 includes the upper bar portion 38 which is pivoted in the barrel 35, and includes the side portions 39 and 40, which are laterally bowed outwardly 100

from each other intermediate their ends, so that said bars 39 and 40 may be flexed in order to secure the clamping action between the jaw and roller portions of the invention as will subsequently appear. The frame 13 includes the outer cross bar portion 42 which rotatably receives a bushing 43 thereon, and upon which bushing a rubber covering 44 of a flexible nature is disposed. It is to be noted that the bar portions 38, 39, 40 and 42 of the frame 13 are preferably disposed in the same plane, and the point of pivotal connection of the frame 13 in the barrel 35 is so that the planes of the frames 12 and 13 may lie parallel when the parts 15 and 16 carried by said frames are in their clamping relation.

The jaw and roller structures 15 and 16 of the improved clasp A are relatively long, it being preferred that the jaw 15 be longer than the roller 16, to facilitate entrance of the roller structure 16 between the side bar portions 24 and 25 of the frame 12.

The operation of this clasp is apparent. The elastic or supporting portion B is looped at the lower end about the connecting element 22, as is illustrated in Figures 2 and 3 of the drawing, to support the clasp A in a depending relation from the member B. The upper edge of the garment C to be supported is then slipped between the jaw and roller structures 15 and 16, and by forcing the frame portions 12 and 13 together the side bar portions 39 and 40 of the frame 13 will flex outwardly laterally as the jaw and roller structures 15 and 16 are moved toward each other, and in this respect the obtusely disposed portion 26 of the frame 12 may also yield slightly, with a spring action, so that the frames 12 and 13 may move into the relation illustrated in Figure 2 of the drawing, and in which position the jaw and roller structures 15 and 16 are in a locked clamping engagement, past dead center, so to speak, and tightly clamp the garment C between the rubber covering portions 30 and 44, as is illustrated in Figure 2 of the drawing. It is to be noted that with this clamping action a relatively broad surface of the garment C is held between the jaw and roller structures 15 and 16; the improved clasp A differing in this respect from conventional clasp structures which ordinarily grasp the garment at a single spot, resulting in its tearing when any considerable force tends to pull the same away from the clasp.

From the foregoing description of this invention it is apparent that a novel type of clasp has been provided which acts upon a novel principle in effecting its clamping action. Of course, the frame portions of the clasp may be so devised that the spring action tending to lock the jaw 15 and roller

16 in their clamping relation may be obtained otherwise than herein specifically set forth.

Various changes in the shape, size, and arrangement of parts may be made to the form of the invention herein shown and described, without departing from the spirit of this invention or the scope of the claims.

I claim:

1. In a clasp of the class described a pair of spring frames, each frame formed from a strand of resilient material bent to provide side bars and upper and lower bars, a bearing carried by the upper bar of one frame and rotatably receiving the upper bar of the other frame to pivotally connect the same to the first frame, one of said frames being longer than the other and having its side bars laterally offset adjacent their lower ends and having a cylindrical shaped gripping member upon its lower bar, the other frame having its side bars bent outwardly for overlapping engagement with the side bars of the first frame and having a roller upon its lower bar which may be moved into engagement with the gripping member of the first frame to flex the offset end of the first mentioned frame so that the gripping member and roller may be positioned in a clamped relation.

2. In a clasp of the class described a pair of spring frames, a connecting member rigid with an end of one of said frames and pivotally receiving an end of the other frame therein, a roller supported at the free end of one of said frames and a cylindrical shaped part fixed at the free end of the other frame in such relation that they may be moved into abutting relation to normally spring the frames with sufficient force to hold the jaw and roller in a firm clamped relation.

3. A clasp comprising a frame portion having the lower end thereof laterally offset with a sleeve fixed thereon, a second frame having side bar portions which may be laterally flexed to spring the same, means pivotally connecting the second frame to the first mentioned frame at a point on the first mentioned frame remote from the sleeve thereof, and a roller rotatably supported on the second mentioned frame at its free end of less length than said sleeve and adapted to move into abutting contact with the sleeve to spring the frames slightly for holding the sleeve and roller in abutting clamped relation.

4. In a clasp of the class described a spring frame including side bar portions offset laterally in obtuse angular relation at their lower ends, an elongated member fixedly supported by said frame at the free ends of said obtusely disposed portions of the bars of said frame, a second frame pivotally connected to the first mentioned frame

at a point remote from its member, said second frame including side bar portions laterally bowed outwardly from each other, and a roller supported at the free end of said 5 second mentioned frame of less width than the member of the first mentioned frame, so that the roller of the second frame may move into the area between the bars of the first mentioned frame and into abutting 10 locked relation with the member on the first mentioned frame incident to flexing of the bar portions of said frames.

DR. WALTER W. CRAM.
